UNITED STATES PATENT OFFICE

2,259,944

BOOT AND SHOE MANUFACTURE

Alfred Vamos, New York, N. Y., assignor to Friedberger-Aaron Manufacturing Company, Philadelphia, Pa., a corporation of Pennsylvania

Application May 8, 1940, Serial No. 333,879

5 Claims. (Cl. 36—51)

This invention is directed to an improvement in boot and shoe manufacture, and more particularly relates to the provision of an improved binding and reinforcing means for shoe uppers formed in whole or in part of stretchable material.

As disclosed in my Patent No. 2,184,261, an improved type of shoe may be produced by making the upper in whole or part of stretchable material, in particular a stretchable plied material consisting of stretchable leather having an elastic backstay.

In finishing the upper edge of such shoes around the foot opening the elastic fabric is skived away, as shown in my said patent, and the exposed portion of leather folded upon itself and stitched or cemented in place. Such construction, while furnishing a neatly rounded edge, is not wholly satisfactory in that the edge so formed is not elastic, whereas to preserve the appearance and shape of the shoe upper around the foot opening the edge portion should have even greater elasticity than the rest of the elastic portion of the shoe.

It has also been proposed in United States Patent No. 2,184,082 to Roberts to provide an elastic reinforcing tape for this edge portion to increase the elasticity thereof, but this necessitates an additional operation, and detracts from the neatness of the edge formed.

Now in accordance with this invention, I provide a simple and expeditious means of finishing and reinforcing the raw edge of an elastic upper. I accomplish this by providing an elastic tape precoated with a pressure sensitive cold cement in conveniently usable form, which tape may be easily and quickly secured to the raw edge of the shoe upper around the foot opening to provide a neat and attractive binding and reinforcement therefor.

In the accompanying drawing the nature and mode of use of my improved elastic binding and reinforcing tape is shown. In the drawing:

Figure 1 is an elevation showing a shoe to which my improved binding has been applied;

Figure 2 is a section through the shoe upper adjacent the edge forming the foot opening showing a step in the application of my improved binding;

Figure 3 is a section on the line 3—3 in Fig. 1, and

Figure 4 is an enlarged view of a portion of my improved binding tape showing the elements of which it is composed.

Referring first to Fig. 4, my improved binding

comprises a narrow strip of woven or braided elastic webbing 1 having embodied therein fine elastic warp threads 3, a narrow strip of thin paper tape 5, coated on both faces with a pressure sensitive cold cement composition 6, and secured by said adhesive to said webbing 1 so as to cover not more than one-half the width thereof from one edge, and, if desired, a protective strip 7, of, for example, crinkled paper, overlying tape 5 and protecting the adhesive coating 6 on the exposed face thereof.

The paper tape 5, together with the protective covering 7 may conveniently be applied to a strip of webbing 1 by feeding the two strips, with an adhesive face of tape 5 in contact with the face of strip 1, through a set of pressure rolls.

When my improved binding is to be applied to the edge of the shoe upper, which, as shown in Figs. 2 and 3, is composed of an outer layer 9 of stretchable leather and an inner layer 11 of elastic fabric cemented together, an edge of the webbing 1 will be secured to the shoe upper by a line of stitching 13, as shown in Fig. 2. The stitching 13 may be a zigzag stitch, or may be made with elastic thread so as not to interfere with the elasticity of the binding or shoe upper. The protective strip 7 may be left in place during this operation, as shown, or may be removed to expose the adhesive surface of tape 5, whichever is more convenient.

Following this operation, the protective strip 7 will be removed, if this has not already been done, and the binding will be folded over the raw edge of the shoe upper, concealing the stitching 13, and secured to the inner face thereof by the adhesive on tape 5, as shown in Fig. 3. With certain machines this can be accomplished in almost the same operation as the stitching, the sewing mechanism being followed by a folding and pressing mechanism.

The raw edge of the elastic shoe upper will now be bound and reinforced by an elastic binding, but the presence of the inelastic tape 5 would seem to negative such elasticity. However, the tape 5, as stated, is formed of thin paper, or other easily frangible material, so that when the bound shoe upper is stretched a few times by hand the tape 5 is broken up into a great number of disconnected particles which do not interfere with the stretchability of the binding, and the webbing 1 becomes cemented directly to the fabric 11 by the adhesive 6 originally coated on both sides of tape 5.

It will be appreciated that the details set forth are merely illustrative of my invention, and that

various modifications therein may be made without departing from the scope of my invention.

I am aware that it has been proposed to produce a shoe piping in which a textile tape coated with adhesive on both faces is secured to a leather piping strip, but such construction, while satisfactory for non-elastic shoes, could not be used with elastic materials because of the non-elasticity of the textile tape.

What I claim and desire to protect by Letters Patent is:

1. An article of manufacture comprising an elastic shoe upper, an elastic binding strip, and a non-elastic tape formed of readily frangible material coated on both faces with a pressure sensitive cold cement, the strip being folded over the edge of the upper and the tape being interposed between the folded over portion of said strip and the opposite side of the upper to secure said strip to said upper.

2. An article of manufacture comprising an elastic shoe upper, an elastic binding strip, and a thin, readily frangible paper tape coated on both faces with a pressure sensitive cold cement, the strip being folded over the edge of the upper and the tape being interposed between the folded over portion of said strip and the opposite side of the upper to secure said strip to said upper.

3. An elastic binding tape for binding and reinforcing elastic shoe uppers comprising a narrow strip of elastic fabric, and a non-elastic tape formed of readily frangible material coated on both faces with a pressure sensitive cold cement overlying said strip along one margin thereof and secured thereto by means of the cement coating on one face of said tape.

4. An elastic binding tape for binding and reinforcing elastic shoe uppers comprising a narrow strip of elastic fabric, and a thin, readily frangible paper tape coated on both faces with a pressure sensitive cold cement overlying said strip along one margin thereof and secured thereto by means of the cement coating on one face.

5. An elastic binding tape for binding and reinforcing elastic shoe uppers comprising a narrow strip of elastic fabric, a non-elastic tape formed of readily frangible material coated on both faces with a pressure sensitive cold cement overlying said strip along one margin thereof and secured thereto by means of the cement coating on one face of said tape, and a temporary protective covering adhered to the free face of said tape to protect the adhesive coating thereon.

ALFRED VAMOS.
